UNITED STATES PATENT OFFICE.

ALBERT H. SHILLMAN, OF BALTIMORE, MARYLAND.

POCKETBOOK.

Application filed January 29, 1926. Serial No. 84,536.

This invention relates to pocketbooks, purses and the like and more particularly to a method whereby such articles may be easily and conveniently decorated by hand. It has been the usual practice in the manufacture of ladies' handbags, pocketbooks and purses to decorate such articles by methods involving the use of machinery. Individuality of design was thus necessarily reduced to a minimum as were the artistic effects so created demanded by the customer. Further, it was often the case that those who purchase such articles desired to provide their own decorations thereon. Until now, however, this has not been possible by reason of the fact that no means have ever been developed which provided for the sale of and disposition of pocketbooks and the like which, while substantially complete as such, were yet adapted for individual decoration.

The principal object of this invention, accordingly, is the provision of such a construction in pocketbooks or purses which, while substantially complete as such, yet nevertheless are adapted for individual hand decoration.

A further object of this invention is the provision of a construction in pocketbooks and the like which is at once as readily adapted for the application of various decorative designs as it is simple and inexpensive to produce.

A further object of this invention is the provision of an auxiliary cover or flap for the pocketbook, which cover or flap is secured permanently along one edge thereof to the pocketbook thus providing a means on which the individual decorative design may be carried out without the necessity for disturbing the pocketbook itself.

A still further object of this invention relates to the method of arranging the several elements of the pocketbook such that the latter is provided with a means which is readily adapted to any kind of individual decoration.

Various other objects and advantages will appear hereinafter.

The invention consists substantially in the combination, location and relative arrangement of parts, all as will be more fully hereinafter set forth, as shown in the accompanying drawings and finally pointed out in the appended claims.

Referring to the accompanying drawings:

Fig. 1 is a view in perspective showing a pocketbook having an auxiliary flap arranged thereon, this flap being shown partly decorated.

Fig. 2 is an end view of the upper portion of the pocketbook showing the particular manner of securing the flap in position.

Fig. 3 is a view in cross section showing the manner of securing the free edge of the auxiliary flap to the pocketbook.

Fig. 4 is an end view of a modified form of the invention.

Fig. 5 is a view in cross section showing the manner of joining together the free edges of the modified form of pocketbook shown in Fig. 4.

The same part is designated by the same reference numeral wherever it occurs throughout the several views.

In the drawings, both in Figures 1 and 2, 10 designates generally the pocketbook to which the invention has been applied. In the construction shown in Fig. 1 the pocketbook 10 is of the usual construction both inside and out except for the fact that the side 11 thereof is covered by an auxiliary flap or cover 12. This flap or cover 12 is secured to the pocketbook along the upper edge thereof preferably by means of a row of stitching 13. As is most clearly shown in Figure 2 this stitching 13 is concealed beneath the hand strap 14 of the pocketbook.

The sides of the pocketbook 10 are provided with no decoration, the cover being of plain cloth or other material. It is for the decorative design on the front of the pocketbook that the auxiliary flap 12 is provided. The outline of this decorative design 15 for the purse is drawn or otherwise impressed on the auxiliary flap 12. In view of the fact that this flap is only secured along its upper edge its main body is free to be handled for the purpose of working the decorative design 15, this being accomplished by the usual expedients of embroidery, painting or the sewing of various colored or steel beads or the like, this last expedient of beading being the one that is preferable and in favor at this time. The design when completely worked out or filled in takes the form indicated by the 112

reference numeral 16 in Fig. 1 of the drawing.

Upon the completion of the decorative design, as when all the beads are sewed in place, the side and bottom edges of the flap 12 have their free edges inturned as at 17 whereupon these inturned edges are secured, as by stitching, to the side and bottom edges of the pocketbook in the manner indicated by 18 in Figure 3.

In the modification shown in Fig. 4 instead of providing a substantially complete pocketbook or purse having an auxiliary flap for decorative purposes, the covering material 19 on one or both sides of the pocketbook is freely disposed along its side and bottom edges with respect to the base 20 of the pocketbook proper. This base is preferably made up of an interior lining 21 to which is secured in any suitable manner, preferably by pasting, a cardboard or similar backing 22. The side and bottom edges of both the interior lining 21 and exterior covering material 19 are respectively turned over as indicated at 23 and 24 and adapted to be joined together when the decorative design is completed, also preferably by pasting, as indicated in Figure 5.

In a manner similar to that described in connection with the construction shown in Figure 1, and before the cover 19 is pasted in place, an outline of the decorative design is initially developed on the exterior cover 19 of the pocketbook which design is subsequently worked out in any suitable manner.

It will thus be seen that there has been provided by means of this invention a construction of pocketbook by which one is enabled to effect any desired design on a pocketbook, purse or other similar article suitable to one's own taste. Not only this but the invention makes possible the distri-

bution of an article in an incomplete and unfinished condition whereby those desiring to do so may work out any design according to their own artistic dictates, the elements of the pocketbook being arranged in such manner that they may be readily and easily secured together to effect the completed pocketbook without the use of any special machinery.

It is to be understood that other variations and modifications of the arrangement herein disclosed may be conceived and devised and still fall within the spirit and scope of this disclosure. Accordingly, it is intended that the appended claims be construed broadly to cover these various modifications.

What is claimed as new and useful is:

1. An article of the class described comprising a pocketbook substantially complete in itself, in combination with an auxiliary cover permanently attached to the top of said pocketbook, the main body of said cover being free of said pocketbook and of an area substantially equal to that of the side of the pocketbook, and means for attaching the sides and bottom of said cover to the pocketbook upon the working out of a predetermined decorative design thereon.

2. An article of the class described comprising a pocketbook in combination with an auxiliary cover permanently attached to the top of said pocketbook, the main body of said cover being free of said pocketbook and of an area substantially equal to that of the side of the pocketbook, and means for attaching the sides and bottom of said cover to the pocketbook upon the working out of a predetermined decorative design thereon.

In testimony whereof, I hereunto affix my signature.

ALBERT H. SHILLMAN.
